ADDING MACHINE

Chester J. Abend, Camillus, and Thomas E. Hanson, Syracuse, N.Y., assignors to SCM Corporation, a corporation of New York

Filed Apr. 20, 1964, Ser. No. 79,605

Term of patent 14 years

(Cl. D64—11)

FIGURE 1 is a front perspective view of an adding machine showing our new design;

FIGURE 2 is another front perspective view thereof as it appears with the keyboard cover attached thereto;

FIGURE 3 is a left side elevational view of the adding machine of FIGURE 1;

FIGURE 4 is another left side elevational view thereof as it appears with the keyboard cover attached thereto;

FIGURE 5 is a front elevational view of the adding machine of FIGURE 1;

FIGURE 6 is a top plan view of the adding machine of FIGURE 1; and

FIGURE 7 is a rear elevational view of the adding machine of FIGURE 1.

We claim:

The ornamental design for an adding machine, substantially as shown and described.
